UNITED STATES PATENT OFFICE.

CARL STAHL, OF GALESBURG, ILLINOIS, ASSIGNOR TO VICTOR CASKET HARDWARE COMPANY, OF GALESBURG, ILLINOIS.

DESIGN FOR A HANDLE FOR A BURIAL CASKET.

Application filed October 26, 1925. Serial No. 15,258. Term of patent 7 years.

To all whom it may concern:

Be it known that I, CARL STAHL, a citizen of the United States, residing at Galesburg, in the county of Knox and State of Illinois, have invented a new, original, and ornamental Design for a Handle for a Burial Casket, of which the following is a specification, reference being had to the ac-

companying drawing, forming part thereof.

The figure is a perspective view of a handle for burial caskets, showing my new design.

What is claimed is:

The ornamental design for a handle for a burial casket, as shown.

CARL STAHL.
